CLAIM

The ornamental design for a Christmas light repair tool as shown and described.

DESCRIPTION

FIG. 1 is a top-front-right side perspective view of a tool attachment device embodying our new design;

FIG. 2 is a bottom-rear-left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged and partial right side elevation view of portion 9 shown in FIG. 6.

The dash-dash broken lines in the drawings depict portions of the Christmas light repair tool that form no part of the claimed design.

The dash-dot broken lines in FIGS. 6 and 9 are provided for the purposes to indicate the area of enlargement and do not represent actual structure. These dash-dot broken lines are forms of annotation and are not part of the claimed design.
